C. L. McCUEN

EXPANSION VALVE FOR REFRIGERATING MACHINES AND THE LIKE

Filed Nov. 1, 1919

UNITED STATES PATENT OFFICE.

CHARLES L. McCUEN, OF EVANSTON, ILLINOIS, ASSIGNOR, BY MESNE ASSIGNMENTS,
TO DELCO-LIGHT COMPANY, OF DAYTON, OHIO, A CORPORATION OF DELAWARE.

EXPANSION VALVE FOR REFRIGERATING MACHINES AND THE LIKE.

Application filed November 1, 1919. Serial No. 335,034.

To all whom it may concern:

Be it known that I, CHARLES L. McCUEN, a citizen of the United States, residing at Evanston, in the county of Cook and State 5 of Illinois, have invented certain new and useful Improvements in Expansion Valves for Refrigerating Machines and the like, of which the following is a specification.

The invention relates to an improved 10 form of expansion valve, particularly designed to be used in connection with refrigerating apparatus of the compression type, in which there is employed the usual compressor, a condenser and an expansion 15 chamber, and the said valve is an improvement upon the type of expansion valve shown in the prior patent to F. W. Wolf No. 1,291,334 granted January 14, 1919, expansion valves of this type being introduced into the system in the connections 20 between the condenser and the expansion chamber, the improved valve being particularly adapted for use in refrigerating systems of the character employing a refrigerant which boils at atmospheric pressure 25 at a sufficiently low degree below the freezing point to produce the temperature required in the refrigerator at atmospheric pressure.

It is the primary object of the invention 30 to so construct a valve of the described character as to reduce to a minimum the likelihood of the valve being rendered inoperative or held in an inoperative position 35 by the accumulation of foreign materials in the vicinity of the valve seat.

It is a further object of the invention to 40 provide in a valve of the described character improved means for controlling the moving parts of the valve throughout all its operating movements and adjusted movements in such a manner as to prevent the valve from becoming unseated by tilting or canting at any time during its operation when 45 intended to be seated.

It is a further object of the invention to 50 provide an expansion valve of the described character which is so constructed that it may be easily assembled and likewise easily taken apart for purposes of adjustment after its installation in a refrigerating machine.

It is a further object of the invention to 55 provide certain improvements in a valve of the described character whereby the parts

of the valve liable to wear and needing adjustment or renewal are made easily detachable and removable, thereby attaining economy in manufacture as well as in repairs should repairs or renewal of parts become desirable or necessary during the life 60 of the valve.

Other objects of the invention will appear from the following description which is directed to the preferred embodiment of the 65 invention as depicted also in the drawing, the features of novelty being set forth in the appended claims.

In the drawing, Fig. 1, is an end elevation view of the valve and Fig. 2 is a side elevation of same with a part thereof broken away showing the valve casing in section adjacent the outlet port and duct of the valve. Fig. 3 is a vertical sectional view through the complete device of Figs. 1 and 75 2 illustrating the details of construction, particularly of the interior movable parts of the valve.

The reference character 10 indicates generally a casting or valve housing comprising an approximately circular plate indicated by the reference character 11 with a lateral extension 12 near the central part thereof, having a hollow interior as indicated at 13, 14, the interiors 13, 14 being separated by a perforated ledge 15 having a valve seat as indicated at 16 formed around the perforation in said ledge. The outer extremity of the projection 12 is screw threaded as illustrated in Fig. 3 to take the angle pipe fitting 17, which is adapted to be connected with the intake pipe 18 of the system, normally leading from the condenser to the expansion valve. The angle fitting 17 may be provided with the integral 95 wings or brackets 19, 20 perforated as illustrated in Fig. 2 for attachment of the valve to some stationary or fixed part of the refrigerator or apparatus connected therewith for supporting the valve.

21 is the valve proper, preferably formed with a conical surface as illustrated in Fig. 3 and being provided with a valve stem 22 of elongated form extending through the valve opening into and through the chamber 13 into an enlarged chamber 23 formed on the reverse side of the plate 11 and closed by a substantially hemispherical plate 24, which is constructed so as to be detachably secured to the outer circumference of the plate 110

11 by a plurality of retaining bolts 25 passing through registering openings in said parts 11 and 24.

A circular diaphragm preferably formed 5 of a thin sheet of metal as brass, copper or analogous material is interposed between the plates 11 and 24 so as to form a partition or division in the chamber 23, such diaphragm being indicated by the reference 10 character 26, Figs. 2 and 3, and being secured in position by the retaining bolts 25, the joint between the plates and said diaphragm being closed by the use of suitable gaskets, as indicated by the reference characters 27, 28 Figs. 2 and 3. There is a supplemental chamber formed in connection with the chamber plate 24 as indicated by the reference character 29 to receive the extended end of the valve stem 22. This 15 chamber 29 is formed preferably by an enlarged central perforation in the hemispherical plate 24, which is covered by the outwardly extending closed cap 30, which may be screw threaded as illustrated, or otherwise 20 suitably secured to the plate 24. The stem 22 of the valve passes laterally into the outer chamber 29 where it is connected with suitable elastic means tending normally to hold the valve closed on its seat, the outer 25 extremity of the valve stem being screw threaded to receive the internally threaded outer extremity of a tubular member 31 which extends laterally from the threaded portion on the same and encircles or 30 surrounds the stem 22 of the valve, there being a peripheral enlargement 32 formed thereon with an extension of the tubular portion beyond the enlargement 32 screw threaded to 35 take a binding nut 33 adapted to clamp and screw the said tubular member and the stem 40 of the valve in rigid connection with the diaphragm 26 at its center. Suitable gaskets as indicated by the reference characters 45 35, 36 may be employed to secure a gas tight joint so that the chamber 23 will be divided 50 by the diaphragm plate 26 into two closed compartments. The outer extremity of the tubular member 31 surrounding the stem of the valve is threaded on its outer periphery 55 and carries a perforated screw threaded plate provided with a flanged periphery as indicated by the reference character 56, which is thus adjustable in relation to the 60 valve stem and said tubular part connected therewith for the purpose of receiving and retaining the outer extremity of a coil compression spring 37, the inner extremity of 65 which engages a plate 38 brazed to, or otherwise suitably secured upon the inner wall 70 of the chamber plate 24, there being a perforation through which the valve stem and tubular connection 31 around the same is loosely passed. A lock nut 39 is threaded 75 on the outer extremity of the tubular member 31 for locking the plate 56 in its ad-

justed positions. In the plate or casting 10 of the valve chamber there is provided a radially extending boss which provides a socket for the attachment of pipe 41 leading to the expansion coil. 70

In refrigerating systems of the described character it is well known that the refrigerant will be maintained under compression on the side of the expansion valve communicating therewith through the pipe 18. To 75 protect the valve 21 against the introduction of foreign materials a screen is preferably inserted across the chamber 14 on the intake side of the valve 21, as indicated by the reference character 50, Fig. 3. The refrigerant 80 being under compression on the condenser side of the valve 21, obviously, such pressure will tend to cause the valve 21 to remain closed so that the refrigerant will not pass through the valve to the expansion coil, particularly as long as the condition of the refrigerant on the expansion coil or chamber side of the valve and consequently in the chamber 18 on the condenser side of the diaphragm is in such a state or condition 85 that the combined effect of the gas in the chamber 18 and the pressure on the condenser side of the valve will be sufficient to overcome the atmospheric pressure which will maintain in the chambers 29 and 23 in 90 contact with the overside of the diaphragm 26. This balance of forces between the atmospheric pressure on the one hand tending to open the valve and the pressure of the gases on the interior of the system on both 95 sides of the valve and valve seat tending to close the valve will be regulated and determined by adjustment of the coil spring 37, which may be adjusted by means of the adjusting nut 39 and plate 56 described, until 100 the valve will be properly controlled for normal operation under any given condition of atmospheric pressure, which of course will vary according to the altitude in which the device is initially adjusted. While I 110 have shown the outer extremity of the valve stem 22 screw threaded for adjustment in relation to the tubular member 31 connected with the diaphragm, I prefer that such adjustment between the tubular member and 115 the valve stem be only provided for assembling purposes and adjustments at the factory, and that these parts be permanently secured together after such factory adjustment by soldering or otherwise, so that the adjustment of the apparatus will be dependent solely upon the relative movement between the valve stem and the adjusting nut and plate 39 and 56 respectively, which may be 120 adjusted as described for varying the tension of the spring 37 by removing the closure cap 30 and then after the desired adjustment is made with respect to nut 39 and plate 56 on the sleeve 31 connected with the diaphragm and valve stem 22, the chambers 125 130

23 and 29 will again be sealed by replacing the cap 30.

One of the difficulties found in the type of valve shown in the said Wolf Patent No. 5 1,291,334 is due to accumulation of moisture from the atmosphere which will freeze upon the exposed lower surface of the diaphragm plate corresponding to plate 26 of the present device, which normally comes in contact 10 with the refrigerant in the system. The invention obviates this difficulty by closing and sealing the chambers 23 and 29 at substantially atmospheric pressure which will prevent free circulation of atmosphere and 15 consequent accumulations of moisture therein, which might become frozen and impede the working of the movable parts of the valve.

Another important feature of the present 20 invention resides in the elongated character of the valve stem 22 insuring that the valve 21 will rise and fall in a substantially lateral direction and be retained at all times in its movements substantially perpendicular 25 to the normal or undeflected plane of the diaphragm 26 in its position of rest, insuring at all times proper seating of the valve.

In the operation of the valve in a refrigerating system of the described character, it is well understood that condenser pressure of the refrigerant will maintain at all times in the pipe 18 leading to the condenser and in the chamber 14 adjacent the valve 21 35 which will remain closed on its seat so long as the substantially atmospheric pressure within chambers 23 and 29 is not sufficient to overcome the pressure in chamber 13 and in that part of the system leading from the 40 extension valve to the expansion coil. However, decrease below a predetermined degree of the pressure maintained in the expansion coil by reason of the operation of the ordinary condenser pump, which is in the usual 45 manner connected with the expansion coil, will cause the substantially atmospheric pressure on the diaphragm to unseat the valve against the reduced area of pressure on the top of the valve on the condenser side 50 thereof with the result that such unseating of the valve will permit quantities or slugs of the refrigerant to pass through the valve and enter the expansion coil until such time 55 as the pressure therein will be sufficient to counteract the substantially atmospheric pressure on the diaphragm, causing the valve to be reseated.

By means of the adjustments described, by varying the tension of the spring 37 it will 60 be seen that the valve may be caused to operate at any desired pressure within the expansion coil, thus regulating the temperature of the refrigerant therein.

In order that the invention might be understood the details of the preferred em-

bodiment have been set forth, but it will be apparent that persons skilled in the art may resort to various modifications without departing from the purpose and spirit of my invention.

70

I claim:

1. In a device of the described character, the combination with a valve chamber provided with passages adapted to have operative connections with a fluid circulatory system, a wall dividing the said chamber into two compartments, each of which is in communication with the said respective passages leading to the circulatory system, a valve seat adjacent an opening in the said wall, a so valve co-operating with said valve seat, a valve stem connected with the valve, a flexible diaphragm in one of said compartments, means for connecting said valve stem with said diaphragm, including a sleeve connected 85 at one end to the diaphragm and at the other end to the valve stem, and a cover closing the said compartment containing the diaphragm, being arranged to exclude moisture in the surrounding atmosphere from contact with the diaphragm.

2. In a device of the described character, the combination with a valve chamber provided with passages for connection with a fluid circulatory system, a wall dividing the 95 said chamber into two compartments each of which compartments is in communication with one of the said passages, a valve seat adjacent an opening in the said wall, a valve co-operating with said valve seat, an elongated valve stem secured to the valve and extending into one of the said compartments, a flexible diaphragm secured to the walls of the compartment into which the said 100 valve stem extends, there being an opening in said diaphragm through which the said valve stem is extended, means for forming a gas tight union between the said valve stem and the said flexible diaphragm, a cover for the said compartment containing 105 the said diaphragm and valve stem, means connecting the said valve stem with the flexible diaphragm, including a sleeve connected at one end of the diaphragm and at the other end to the valve stem, and elastic 110 means for resisting the movement of said 115 valve in one direction.

3. In a device of the described character, the combination with a valve, of a valve stem connected therewith, a chamber, a wall 120 in said chamber provided with an opening therein, a valve seat in the said wall surrounding said opening, a valve stem connected with said valve and extending through the said valve opening into said 125 chamber, a flexible diaphragm in said chamber providing a gas tight division between two compartments in said chamber, there being an opening in said diaphragm through which the said valve stem extends, means 130

for forming a gas tight union between the valve stem and the diaphragm comprising an elongated sleeve and suitable means for clamping said sleeve in contact with the diaphragm, a plate secured to said sleeve, means for adjusting said plate in relation to said sleeve, a cover for said chamber adapted to exclude moisture from contact with the diaphragm in the chamber, a ledge 10 or stop mounted on said cover, and resilient means interposed between the said ledge or stop and the said adjustable plate on the said valve stem sleeve.

4. In a device of the described character, 15 the combination with a valve chamber of a valve and a valve seat therein, an elongated stem connected with said valve, a flexible diaphragm dividing said chamber into a plurality of compartments, a cover plate 20 covering the end of the valve chamber on the side of the diaphragm remote from the said valve and valve seat, there being an opening in the said flexible diaphragm through which the valve stem is extended, 25 means for securing a gas tight union between the valve stem and the flexible diaphragm adjacent the valve stem opening therein, said means comprising in part a sleeve surrounding a portion of the valve 30 stem on the side of the flexible diaphragm remote from the valve, and means for normally seating the said valve comprising an elastic means for resisting the movement of said valve in one direction and an 35 adjustable device secured to the said valve stem sleeve.

5. In a device of the described character, 40 the combination with a valve casing having a partition or wall therein and dividing the casing, there being an opening in said partition or wall, a valve seat around said opening, a valve co-operating with said valve seat, a substantially circular flange forming an enlargement of the wall of said valve 45 chamber, a diaphragm secured to the periphery of the said enlarged circular portion of the valve chamber, a cover plate secured to the said enlarged portion of the valve chamber, and forming a compartment therewith, a second cover plate secured to an opening in the first said cover plate and forming a continuation of the compartment on the reverse side of the diaphragm from the said valve, there being an opening in 55 the said diaphragm, a valve stem connected with the said valve and extending through the opening in the diaphragm, a sleeve sur-

rounding a portion of the said valve stem, means for forming a gas tight union between said sleeve and that portion of the said diaphragm around the said opening therein, adjustable means secured to the said sleeve surrounding the valve stem, a part in fixed relation with said valve chamber, and a coil spring interposed between said adjustable 65 means and said part.

6. In a device of the described character, 70 the combination with a valve chamber provided with passages adapted to have operative connections with the fluid circulatory system, a wall dividing said chamber into two compartments, each of which is in communication with the said respective passages leading to the circulatory system, a valve seat adjacent an opening in the said wall, 75 a valve co-operating with said valve seat, a flexible diaphragm in one of said compartments of the valve chamber and being spaced apart from the said wall bearing the valve seat, an elongated valve stem connected with the valve and with the diaphragm and extending on the side of the diaphragm opposite the valve, and elastic means connected with the extended portion of the valve stem on the side of the diaphragm opposite the valve for normally seating the valve. 80

7. In a device of the described character, 85 the combination with a valve chamber provided with passages adapted to have operative connections with the fluid circulatory system, a wall dividing said chamber into two compartments, each of which is in communication with the said respective passages leading to the circulatory system, a valve 90 seat adjacent an opening in the said wall, a valve co-operating with said valve seat, a flexible diaphragm in one of said compartments of the valve chamber and being spaced apart from the said wall bearing the valve seat, an elongated sleeve surrounding the elongated valve stem, said sleeve being secured to form a gas tight union with the diaphragm and having the free end thereof secured to the free end of the valve stem on the side of the diaphragm opposite the valve, 95 adjustable means secured to the free end of the sleeve, a stop secured to the chamber wall and elastic means interposed between the last said means and said stop. 100

In testimony whereof I have signed my name to this specification, on this 24th day of October A. D., 1919.

CHARLES L. McCUEN.
